UNITED STATES PATENT OFFICE.

WILLIAM S. DOLBEY, OF BROOKLYN, NEW YORK.

DESIGN FOR A FINGER-RING.

SPECIFICATION forming part of Design No. 13,370, dated October 31, 1882.

Application filed June 21, 1882. Term of patent 3½ years.

To all whom it may concern:

Be it known that I, WILLIAM S. DOLBEY, of Brooklyn, county of Kings, and State of New York, have invented a new and original Design 5 for Finger-Rings, of which the following is a full, clear, and exact description, reference being had to the accompanying drawings, and to the letters of reference marked thereon.

The drawings or photographic illustrations 10 are taken from a ring with my new design applied in connection therewith, Figure 1 representing the ring, and Figs. 2, 3, and 4 the setting detached therefrom.

The design relates particularly to that part 15 of the ring known as the "setting."

A represents the crystal, and B the annulet. Upon the under and flat side of the crystal is engraved any desired "floral," "bird," or other appropriate device or ornamentation, which is 20 painted in colors to imitate or resemble the object copied from nature, or in accordance with the taste of the artist. The crystal, owing to its peculiar form and lens construction, possesses certain magnifying powers which im- 25 part to the engraved and painted device a beautifully clear, liquid, stereoscopic appearance and color not presented by other forms of jewelry-settings. The crystal or stone of this shape, with the addition of a backing of mother- 30 of-pearl, colored metal, or other substance best

calculated to enrich the contrast, and thereby enhance the artistic effect (and brilliancy) of the colors introduced in the device, is then set in a "box" or close mounting. The box is represented at C.

The part of the ring which holds the crystal is composed of an oval frame, of size suitable to closely fit the crystal and its box, with square cramps D D at the ends and sides, substantially as shown in the drawings, and the same 40 may be ornamented by studding of small stones, or by engraving and chasing of the plain metal.

The ring or annulet may of course be modified or ornamented to suit the taste, and the bird and flower is only one cut that may be 45 used.

I claim—

The design for a finger-ring herein shown and described, consisting of the oval crystal A, ornamented and illuminated upon its flat 50 side or back, the metallic box C, and the ring having the square cramps D.

In testimony that I claim the foregoing I have hereunto set my hand in presence of two witnesses.

WM. S. DOLBEY.
